D. 159,149 6/1950 Glass ..... D7/141 X
D. 167,300 7/1952 Brooks D7/141

[75] Inventor: Ellen B. Manderfield, Syracuse, N.Y.

Primary Examiner—Winifred E. Herrmann
Attorney, Agent, or Firm—Gene O. Enockson

[73] Assignee: General Mills, Inc., Minneapolis,
Minn.

[57] CLAIM

The ornamental design for a fork or similar article,
substantially as shown and described.

[**] Term: 14 Years

DESCRIPTION

[21] Appl. No.: 794,871

[22] Filed: May 9, 1977

[51] Int. Cl. ..... D7—03

FIG. 1 is a front elevational view of a fork or similar
article showing my new design;
FIG. 2 is a rear elevational view thereof;
FIG. 3 is a side elevational view thereof; and
FIGS. 4 and 5 are enlarged sections on the respective
lines 4—4 and 5—5 of FIG. 1.
The essential features of my design reside in the handle
portion as shown in the accompanying drawings.
